UNITED STATES PATENT OFFICE

158,747

PNEUMATIC TIRE

Audrey A. Hobe, Detroit, Mich., assignor to United States Rubber Company, New York, N. Y., a corporation of New York

Application June 21, 1949, Serial No. 3,437

Term of patent 14 years

(Cl. D90—20)

To all whom it may concern:

Be it known that I, Audrey A. Hobe, a citizen of the United States of America, residing in Detroit, county of Wayne, and State of Michigan, have invented a new, original, and ornamental Design for a Pneumatic Tire, of which the following is a specification, reference being had to the accompanying drawing, forming part thereof, wherein:

Fig. 1 is a fragmentary top plan view of a pneumatic tire, showing my new design;

Fig. 2 is a side elevational view of Fig. 1;

Fig. 3 is a sectional view taken along the lines III—III of Fig. 1 in the direction shown by the arrows; and

Fig. 4 is a sectional view taken along the line

IV—IV of Fig. 3, in the direction shown by the arrows.

I claim:

The ornamental design for a pneumatic tire, as shown.

AUDREY A. HOBE.
